RAIL BRACE

George Arnold, Shaker Heights, and Harry A. Schultz, Garfield Heights, Ohio, assignors to Cleveland Frog & Crossing Co., Cleveland, Ohio, a corporation of Ohio

Application November 12, 1948, Serial No. 59,653

18 Claims. (Cl. 238—292)

1

This invention relates to a rail brace such as is applied to a railroad rail to resist any tendency of the rail to turn outwardly from the center of the track and to clamp it to the tie plate, base plate or switch plate on which it rests, thus holding the rail against movements relative to the plate, which latter in turn is secured to a supporting tie as is well understood in the art.

Rail braces of the type contemplated by this invention are most frequently applied against the stock rails along side split switch points but their use is not necessarily limited to such application. Further, braces of this type are frequently made adjustable to compensate for variations in the dimensions of the rail, the seat for the rail and brace, in the brace itself, and also to afford a means of retightening the assembly after wear takes place.

Rail braces employed for this purpose generally have a portion which engages one of the sloping base flanges of the rail and the vertical web of the rail where it merges with the base flanges and a portion which engages the web beneath the rail head. Heretofore the rail braces have been secured to the base plates in rail clamping and bracing position by hold-down or clamping bolts carried by and extending through openings in the base plates and braces.

In the use of the rail braces in track it sometimes occurs that the hold-down bolts become damaged or are sheared off thus necessitating removing the rail brace and remounting the same with new hold-down bolts. Inasmuch as the practice has been to have the hold-down bolts carried by and extend through openings in the base plates with the heads of the bolts located between the base plates and the ties to which the plates are secured, it has been necessary in order to remove the hold-down bolts to first remove the base plates from the ties. This is a disadvantage in maintenance operations and consumes substantial time and labor. Furthermore since the hold-down bolts are mounted in and carried by the base plates and extend through openings therein, it has been necessary to provide the base plates with openings. These openings in the base plates have been located in positions which coincide with that part of the plates subject to the greatest strain in use. This location of the openings in the base plates has been occasioned by the fact that it is customary to provide the rail braces intermediate the side walls of the braces with complementary hold-down bolt receiving openings.

An object of the invention is to provide a rail

2

brace and base plate construction such that the hold-down bolts can be applied to the brace and plate without necessitating removal of the plate from the tie.

Another object is to provide a rail brace and base plate construction such that the initial installation and subsequent maintenance thereof are facilitated and rendered more economical.

Another object is to provide a rail brace and base plate construction such that the hold-down bolts are carried by the rail brace and can be operatively connected to the base plate when secured to a tie and during the installation of the brace and without removal of the plate from the tie.

Another object of the invention is to provide a rail brace and base plate construction such that it is not necessary to have hold-down bolt openings in the base plate, wherefore the provision of weakened zones in the base plate is obviated.

Further and additional objects and advantages not hereinbefore specified will become apparent in the detailed description of several embodiments of the invention which is to follow.

In carrying out the invention it is contemplated to provide the rail brace adjacent its opposite longitudinal side edges and beyond the side walls of the brace with means for operatively connecting the hold-down bolts with the brace and to utilize with such means hold-down bolts of a character that can be operatively connected to the base plate after the base plate has been secured to a tie.

Referring to the accompanying drawings illustrating said several embodiments of the invention,

Fig. 1 shows a rail mounted on a base plate with a rail brace secured in rail clamping position on the base plate, the said rail being shown in transverse section and said base plate and rail brace being constructed in accordance with the invention and being shown in elevation taken looking toward a longitudinal side or edge of the plate and brace.

Fig. 2 is a plan view of the rail, base plate and rail brace shown in Fig. 1 with the head of the rail removed and the web thereof shown in section.

Fig. 3 is a partial elevational and partial sectional view of the rail, base plate and rail brace with the sectional portion of the view taken substantially along line 3—3 of Fig. 2 and with the base plate illustrated as secured to a tie, the elevational portion being taken looking from the end of the tie at the end of the brace and plate and at the side of the rail.

Fig. 4 is a view similar to Fig. 3 but illustrating a different form of base plate and hold-down bolt employed in the construction embodying the invention.

Fig. 5 is a view similar to Fig. 1 but showing a modified form of base plate and rail brace embodying the invention.

Fig. 6 is a view similar to Fig. 2 but of the modified form shown in Fig. 5.

Fig. 7 is a view similar to Fig. 3 but of the modified form shown in Figs. 5 and 6 and is taken substantially on line 7—7 of Fig. 6, and

Fig. 8 is a detached fragmentary longitudinal elevational view of the base plate shown in Figs. 5 to 7 inclusive.

The form of rail brace illustrated in Figs. 1 to 3 inclusive and embodying the invention will first be described. The rail brace is employed with a railway rail indicated generally at 10 and comprising the usual base flanges 11 provided on their upper sides with downwardly sloping surfaces 12. A vertically extending web 13 interconnects the rail base with the rail head 14. The rail is supported on a base plate 15 which in turn is secured to a tie 16 by spikes or other suitable means not shown as it is fully known in the art. The base plate 15 on its upper side is provided with a recess in which the base of the rail is located, with the left hand side of the rail base engaging the base plate at the left hand end of the recess as viewed in the drawings. A fixed abutment member or back stop 17 is illustrated as secured in the recess of the base plate at the right hand end thereof by suitable securing means such as the rivets 18 as is common practice in the art.

The rail brace is for the purpose of clamping and bracing the rail in proper position with respect to the base plate, with the left hand (as viewed in the drawing) base flange of the rail firmly in engagement with the left hand end of the recess in the base plate and to prevent relative movements of the rail with respect to the base plate. This is the usual function of a rail brace as already explained.

The rail brace comprises a brace block, indicated generally by the letter B, and this block may be formed as a casting, forging or in any suitable manner as will be well understood in the art. The brace block B comprises a vertically extending portion 19 which has at its upper end a rail engaging portion 20 that is adapted when the brace is applied to the rail to engage the side of the web 13 of the rail below but adjacent to the underside of the rail head 14, it being noted that clearance is provided between the upper surface of the portion 20 and the under surface of the rail head for the purpose that the portion 20 will exert force against the web 13 of the rail in substantially a horizontal direction and will not exert upward force on the rail head which would tend to tip the rail. The vertical portion 19 and the rail engaging portion 20 of the block B extend longitudinally of the rail.

The block B is provided with a substantially horizontal portion 21 integrally connected to the lower end of the vertical portion 19. This horizontal portion 21 adjacent to the vertical portion 19 is provided on its underside with an inclined surface 22 that engages the downwardly sloping surface 12 of the base flange 11 of the rail. The underside of the horizontal portion 21 of the block has a downwardly extending rib 22a, the right hand side of which rib, as viewed in the drawings, is inclined transversely of the base

plate 15. The horizontal portion 21 of the block B beyond the rib 22a is provided with an overhanging lip 23 which on its underside is provided with a series of serrations or teeth transversely disposed with respect to the lip, with the series extending substantially throughout the length of the lip.

The vertical portion 19 and the horizontal portion 21 including the lip 23 are connected by parallel spaced side walls 24, the upper surfaces of which are formed with a concave curvature extending from the portion 20 to the lip 23. The parallel side walls 24 are located adjacent to but inwardly of the longitudinal front and rear edges or sides of the block. The block B on its opposite front and rear longitudinal edges and outwardly of the side walls 24 is shown as provided with outwardly extending lug portions 25 that are integral with the horizontal portion 21. The front longitudinal edge of the block B is deemed herein as the edge toward which the observer looks in Fig. 1. The lug portions 25 project beyond the longitudinal edges of the base plate 15 as clearly shown in Fig. 2 and are provided with hold-down bolt openings which when the block B is positioned on the base plate 15 overlie said opposite longitudinal edges of the base plate. The bolt openings in the portions 25 are downwardly and divergently tapered to provide the required draft for the casting operation. The shanks 26 have integrally formed at their upper ends the threaded bolt portions 27 which are disposed at a slight angle to the shanks 26 as clearly indicated in Fig. 3. The lower ends of the shanks 26 have integrally formed thereon the bolt heads 28 which, in this instance, are simply enlarged ends of the shanks 26 and are provided with beveled side surfaces 29. The inclined shanks 26 enable the bolts to contact the outer portions of the walls of the openings even though there is substantial clearance between the inner portions thereof and the bolts.

The opposite longitudinal sides of the base plate 15 are provided with undercut recesses 30 elongated somewhat in the longitudinal direction of the base plate to allow for adjustment of the block toward and from the rail and having beveled surfaces 31 with which the beveled surfaces 29 of the bolt heads 28 cooperate.

The threaded upper ends 27 of the hold-down bolts have mounted thereon cap nuts 32 with heavy spring washers 33 interposed between the cap nuts 32 and the upper sides of the lug portions 25.

In initially assembling the rail brace and base plate the latter is positioned on the tie in its approximate location with the rail in the recess of the plate. The hold-down bolts are then positioned with their heads 28 in the undercut recesses 30 of the base plate and with the beveled surfaces 29 of the bolt heads engaging the beveled surfaces 31 of the recesses. The rail brace is approximately positioned on the rail and base plate, it being understood that the hold-down bolts are passed through the openings in the portions 25 of the brace as the latter is thus positioned. The spring washers 33 and the cap nuts 32 are then mounted on the hold-down bolts and slightly tightened down. Then the wedge 34 is inserted to move the brace against the rail until the rail firmly engages the shoulder at the end of the recess in the upper side of the base plate. The serrations or teeth on the wedge and brace ride over each other as the wedge 34 is inserted. When this has been accomplished the

cap nuts are tightened to firmly clamp the rail brace in position and to engage the serrations of the lip 23 with those on the upper surface of the wedge 34. Also the tightening of the nuts will firmly engage the beveled surfaces 31 of the undercut recesses 30 of the base plate with the beveled surfaces 29 of the bolt heads to positively interconnect the rail brace and base plate. When the rail brace has been firmly and properly clamped in position and the rail is correctly located in the recess on the upper side of the base plate then the latter may be permanently secured to the tie in the proper position.

It will have been noted that the hold-down bolts are carried by the rail braces as distinguished from the usual practice of such bolts being carried by the base plates. In case it is necessary to remove the rail braces from the base plates and replace damaged hold-down bolts it will not be necessary to remove the base plates from the ties in order to remove the hold-down bolts. The importance of this is apparent, especially in view of the fact that such base plates are secured to the ties by heavy spikes and are difficult to remove from their secured position. It will thus be seen that should it be necessary to replace the hold-down bolts the operation is greatly facilitated by a construction embodying the invention. It will also be noted that by utilizing the undercut recesses 30 in the base plates to accommodate the heads 28 of the bolts and by the coaction of the beveled surfaces 29 and 31 of the bolt heads and recesses the clamping bolts are operatively connected to the base plates so as to provide a positive clamping and hold-down relationship between the rail braces and base plates while at the same time affording for the ready disconnection of the bolts with respect to the base plates, thus providing easy removal of the rail braces and facilitating replacement of the hold-down bolts. Also it will be noted that the base plates are not weakened by the necessity of providing bolt openings located intermediate the front and rear longitudinal edges of the base plates.

In Fig. 4 a modified form of rail brace and base plate construction is illustrated and insofar as the parts of this modified form are identical with the parts of the form shown in Figs. 1 to 3 inclusive, the same reference characters are employed and the description need not be repeated.

In the form shown in Fig. 4 the base plate 15 differs from the previously described base plate by the omission of the undercut recesses 30. However, in the construction shown in Fig. 4 the opposite longitudinal edges of the base plate 15 extend over recesses 34 formed in the upper corners and at the longitudinal sides of the tie 16. The shanks 26 of the hold-down bolts in the form of construction shown in Fig. 4 have integrally formed on their lower ends in place of the heads 28 hook-like portions 35 which when the rail brace is mounted in position are located in the recesses 34 in the tie. These hook-like portions 35 extend beneath the opposite longitudinal edges of the base plate 15 and the flat upper surfaces of the bolt portions 35 contact the undersurface of the base plate 15. Consequently when the cap nuts 32 are screwed tightly down on the bolts the rail brace will be firmly and positively interlocked with the base plate in its proper assembled position, as will be understood from the description previously given with respect to the installation of the construction shown in Figs. 1 to 3 inclusive.

It will be understood that the form of construction shown in Fig. 4 possesses the same advantages as does the form of construction previously described.

5 In Figs. 5 to 8 inclusive there is illustrated a still different form of construction embodying the invention. Insofar as the various parts of the construction shown in Figs. 5 to 8 are identical with the corresponding parts of the constructions previously described they are indicated by the same reference characters and the description thereof need not be repeated.

In the construction shown in Figs. 5 to 8 inclusive the rail brace block is indicated generally at B'. The block B' includes a vertically extending portion 36 having at its upper end a rail web engaging portion 37. The block B' is also provided with horizontal portions 38 integral with the vertical portion 36 and located adjacent the front and rear longitudinal sides of the block. The horizontal portions 38 are separated by downwardly facing reinforcing channel portion 39 which is integral with the vertical portion 36 and the horizontal portions 38 and extends with a downward curvature from the vertical portion 36 to the lip 40 of the block that overlies the wedge 34. The horizontal portions 38 of the block are provided with hold-down bolt receiving bosses 41, the outer sides of which are curved as indicated. The bosses 41 are provided with vertical openings formed with a downwardly divergent taper to allow swinging movement therein of the shanks 42 of the straight hold-down bolts mounted in said openings, thus facilitating the installation of the brace. The threaded upper ends 43 of the straight hold-down bolts extend above the bosses 41 and are provided with the usual cap nuts 32 and heavy spring washers 33. The lower ends of the shanks 40 42 of the hold-down bolts are provided with semi-cylindrical heads 44.

The opposite longitudinal edges of the base plate 15 are provided with semi-cylindrical recesses 45 which communicate at their upper portions with slots 46. The recesses 45 and slots 46 being located in the longitudinal sides of the base plate the heads 44 and shanks 42 of the hold-down bolts can be positioned, respectively, in the recesses and slots by rocking the bolts away from the rail as the block B' is positioned on the base plate and against the rail, it being recalled that the bolt openings in the bosses 41 allow for such rocking movement of the hold-down bolts.

The rail brace and base plate construction shown in Figs. 5 to 8 inclusive is installed in operative position in substantially the same way as are the previously described forms of construction and hence for brevity the installation of this construction need not be set forth. It will be seen that the hold-down bolts of the last form of construction also are carried by the rail brace rather than by the base plate. Consequently whenever necessary or desirable the hold-down bolts can be removed and replaced without disturbing the connection of the base plate to the tie 16. In addition the last described form of construction possesses all of the advantages hereinbefore enumerated with respect to the previously described forms and accomplishes the purposes and objects of the invention.

Although several preferred embodiments of the invention have been illustrated and described herein it will be understood that the invention 75 is susceptible of various other modifications and

adaptations within the scope of the appended claims.

Having thus described our invention, we claim:

1. In a rail brace construction comprising a block having a rail engaging part and a substantially horizontal part integral with and extending from said rail engaging part and adapted to overlie the base plate on which the rail is mounted, said horizontal part being provided adjacent its opposite longitudinal edges with vertically extending hold-down bolt openings adapted when the block is installed against the rail to be located above the opposite longitudinal edges of the base plate, and vertically extending hold-down bolts mounted in said openings and having their upper ends provided with threads and adapted to mount spring washers and hold-down nuts and their lower ends provided with head portions adapted to be removably interconnected with the opposite longitudinal edges of the base plate when the block is mounted on the base plate in rail engaging position.
2. A rail brace construction as defined in claim 1 and wherein the head portions of the hold-down bolts when in operative position extend inwardly of the opposite longitudinal edges of the horizontal part of the block and are adapted to be located inwardly of the opposite longitudinal edges of the base plate when the block is mounted on the latter in rail engaging position.
3. A rail brace construction as defined in claim 1 and wherein the head portions of the hold-down bolts are shaped to detachably engage in recesses formed in the opposite longitudinal edges of the base plate.
4. A rail brace construction as defined in claim 1 and wherein the head portions of the hold-down bolts are provided with beveled surfaces adapted to cooperate with similarly beveled surfaces formed in the base plate adjacent the opposite longitudinal edges of the latter.
5. A rail brace construction as defined in claim 1 and wherein the head portions of the hold-down bolts are in the form of hooks adapted to underlie the opposite longitudinal edges of the base plate.
6. A rail brace construction as defined in claim 1 and wherein the head portions of the hold-down bolts are of semi-cylindrical configuration and are adapted to removably engage in semi-cylindrical recesses formed in the opposite longitudinal edges of the base plates.
7. A rail brace construction as defined in claim 1 and wherein the hold-down bolt openings in said horizontal part are divergently tapered in a downward direction.
8. A rail brace construction as defined in claim 1 and wherein the hold-down bolt openings in said horizontal part are divergently tapered in a downward direction.
9. A rail brace construction as defined in claim 1 and wherein said horizontal part of said block is provided at its opposite longitudinal edges with outwardly extending lugs provided with said hold-down bolt openings.
10. A rail brace construction as defined in claim 1 and wherein said block is provided with vertical reenforcing portions integrally interconnected with said rail engaging part and said horizontal part and located intermediate the opposite longitudinal edges of said horizontal part, while said hold-down bolt openings are formed

in said horizontal part outwardly of said reenforcing portions.

11. A rail brace and base plate construction comprising, in combination, a base plate adapted to be secured to a tie and provided on its upper side with a recess in which the base of a rail may be mounted, said rail brace including a block having a rail engaging part and a substantially horizontal part integral with and extending from said rail engaging part and overlying the base plate, said horizontal part being provided adjacent its opposite longitudinal edges with vertically extending hold-down bolt openings overlying the opposite longitudinal edges of the base plate, and hold-down vertically extending bolts mounted in said openings and having their upper ends threaded and adapted to mount spring washers and hold-down nuts and their lower ends provided with head portions detachably engaging cooperating portions of the longitudinal edges of the base plate when the block is mounted on the base plate in rail engaging position and acting to positively interconnect the base plate and block when said nuts are screwed down on said hold-down bolts.
12. A rail brace and base plate construction as defined in claim 11 and wherein the head portions of said hold-down bolts extend inwardly of the opposite longitudinal edges of the base plate.
13. A rail brace and base plate construction as defined in claim 11 and wherein said base plate is provided in its opposite longitudinal edges with recesses, while said head portions of said hold-down bolts engage the base plate in said recesses.
14. A rail brace and base plate construction as defined in claim 11 and wherein the opposite longitudinal edges of said base plate are provided with recesses having beveled surfaces, while the head portions of said hold-down bolts are provided with beveled surfaces cooperating with the beveled surfaces of said recesses.
15. A rail brace and base plate construction as defined in claim 11 and wherein the opposite longitudinal edges of said base plate are provided with semi-cylindrical recesses and slots communicating with said recesses, while said hold-down bolts extend through said slots with the head portions of the bolts being of semi-cylindrical configuration and engaging the base plate in said recesses.
16. A rail brace and base plate construction as defined in claim 11 and wherein the opposite longitudinal edges of the horizontal part of said block are provided with outwardly extending lugs in which the hold-down bolt openings are located.
17. A rail brace and base plate construction as defined in claim 11 and wherein said hold-down bolt openings are of downwardly divergent tapered configuration and said bolts can be rocked therein and relative to the opposite longitudinal edges of said base plate.
18. In combination, a railroad tie, a base plate secured thereto and provided on its upper side with a recess in which the base of a rail may be mounted, said tie in its upper longitudinal corners and adjacent said rail being provided with recesses extending beneath the opposite longitudinal edges of the base plate, a rail brace mounted on said base plate and having a rail engaging part and a substantially horizontal part integral with and extending from said rail engaging part and overlying the base plate, said horizontal part being provided adjacent its opposite longitudinal

edges with vertically extending hold-down bolt openings overlying the opposite longitudinal edges of the base plate, and vertically extending hold-down bolts mounted in said openings and having their upper ends threaded and mounting thereon spring washers and hold-down nuts and their lower ends provided with hook-like head portions located in said tie recesses and extending beneath the opposite longitudinal edges of said base plate and engaging the underside of the base plate and detachably and positively interconnecting said block and base plate when said nuts are screwed down on said bolts.
